RATCHET CLAMP ATTACHED OVERALL BUCKLE

Ray R. Roberts, Thomaston, Theodore Russell, Naugatuck, and Robert J. Hodge, West Haven, Conn.

Application July 9, 1943, Serial No. 493,978

2 Claims.

(Cl. 24—73)

This invention relates to garment fasteners and more particularly to a buckle for use in association with an overall shoulder strap for detachably locking said strap tightly thereto.

One object of the invention is to provide an improved overall buckle of the above nature which may be releasably and adjustably locked to the shoulder strap by means of a swinging angle-shaped toggle cross bar.

Another object is to provide an improved overall tight-locking buckle of the above nature having a pair of opposed transverse outwardly curved tongues at its lower end to facilitate the attachment to and removal of the buckle from the overall button.

A further object is to provide a device of the above nature which will be simple in construction, easy to manufacture, easy to install and manipulate, compact, ornamental in appearance and very efficient and durable in use.

With these and other objects in view there has been illustrated on the accompanying drawing one form in which the invention may be conveniently embodied in practice.

In the drawing:

Figure 1 represents a front plan view of a buckle embodying the features and principles of this invention.

Figure 2 is a rear plan view similar to Figure 1 in which the angle bar is shown in locked position.

Figure 3 is a front plan view, similar to Figure 1, showing the buckle and portions of the overall shoulder strap and the overall garment, which is attached to said buckle by a button.

Figure 4 is a longitudinal sectional view of the same, the section being taken on the line 4—4 of Figure 3 looking in the direction of the arrows.

Figure 5 is a transverse sectional view taken on the line 5—5 of Figure 3 looking in the direction of the arrows.

Referring now to the drawing in which like reference numerals denote corresponding parts throughout the several views, the numeral 10 indicates a buckle frame which is provided with a straight top edge 11 and a pair of side edges 12 and 13 which have straight upper portions and convex bottom portions 14 and 15. The buckle 10 is also provided with a substantially flat bottom edge 16 having a central depending convex section 17.

In order to permit the insertion of a shoulder strap 36 through the lower part of the buckle frame, provision is made of a transverse opening 18 into which extends, from the bottom por-

tion of side sections 14 and 15, a pair of tongues 19 and 20 having their inner extremities 21 and 22 spaced apart and curled out of the plane of said frame as clearly shown in the drawing.

By means of this construction the attaching neck 39 of a button 38 secured to an overall garment 37 may readily be passed downwardly between the tongues 19 and 20 with a snap action to permit said neck 39 to engage in a semi-circular central recess 23 located in the upper edge of the convex central section 17 and with the button lying in front of said tongues 19 and 20.

Surrounding the buckle frame at a point just inside the periphery thereof is a raised stiffening rib 24 pressed in the metal, providing a continuous groove 25 on the rear of said buckle body frame 10.

In order to permit the buckle to be detachably locked on the shoulder strap 36 of the overall in any desired adjusted position along the length thereof, provision is made of a pair of parallel rearwardly bent ears 26 and 27 located at the top of the body frame 10.

The ears 26 and 27 are provided with apertures 26a and 27a for receiving the reduced end pins 26b, 27b respectively of an angle shaped toggle crossbar 28 which is adapted to be freely pivoted in said apertures 26a and 27a (see Figure 5).

The toggle cross bar 28 is provided with a relatively wide flat intermediate section 29 which is adapted to extend parallel to the buckle body frame 10 when in locked position shown in Figures 2 and 4, and perpendicular to said buckle frame 10 when in unlocked position respectively.

The intermediate section 29 of the crossbar 28 is provided with a central concave recess 30 adapted to lie substantially parallel with a curved section 18a of the opening 18 in the body of the buckle when in locked position. The section 29 is held in such raised position by a pair of inclined curved tongues 31 and 32 at the side extremities thereof which engage the shoulder strap when the crossbar is locked.

The toggle crossbar 28 is provided at its rear end with a short locking section 33 located substantially at right angles to the intermediate section 29 and said locking section 33 is provided with two aligned spaced rows of teeth 34 and 35, which are adapted to engage the fabric of the shoulder strap 36 with a snap toggle action at a point directly in alignment with the groove 25 on the rear surface of the frame 10.

By means of this construction it will be seen that the crossbar may be readily released by inserting one finger of the user in the recess 30

behind the intermediate section 29, and swinging said crossbar outwardly.

The button 38 previously mentioned is preferably secured to the fabric of the overall garment 37 near the top thereof by means of a pair of spaced clamping disks 40 secured to the neck 39 and embracing said fabric.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a buckle, a substantially rectangular frame having a transverse opening therein, and a straight upper edge, a narrow groove extending below the surface of said frame adjacent said upper edge, a pair of apertured ears upstanding

from the plane of said frame at the opposite sides thereof adjacent said upper edge, a toggle crossbar having a pair of pins on the extremities thereof pivotally mounted in the apertures of 5 said ears to permit said crossbar to swing with respect to said buckle frame, said crossbar having an upstanding short locking section at its upper end which lies at right angles to the plane of said buckle frame and in alignment with said 10 groove when said crossbar is in locked position whereby it will forceably press a shoulder strap in kinked condition into said groove with a strong toggle action, the width of said narrow groove being substantially the same as the thickness of 15 said short locking section.

2. The buckle as defined in claim 1 in which said crossbar has a pair of inclined tongues for engaging said shoulder strap when in locked condition and providing a raised recess therebetween 20 to permit the crossbar to be swung open by the insertion of the user's finger thereunder.
